UNITED STATES PATENT OFFICE.

WILLIAM V. FRANK, OF SPRINGFIELD, OHIO, ASSIGNOR OF ONE-THIRD TO CHARLES OESTERLE AND ONE-THIRD TO GEORGE W. FRANK, OF SPRINGFIELD, OHIO.

OPERATING MECHANISM FOR WASHING-MACHINES.

935,901.

Specification of Letters Patent.

Patented Oct. 5, 1909.

Application filed November 14, 1908. Serial No. 462,545.

To all whom it may concern:

Be it known that I, WILLIAM V. FRANK, a citizen of the United States, residing at Springfield, in the county of Clark and 5 State of Ohio, have invented certain new and useful Improvements in Operating Mechanism for Washing - Machines, of which the following is a specification, reference being had therein to the accompanying drawings.

10 This invention relates to operating mechanism for washing machines, and the object of the invention is to provide a power-driven mechanism of this character which will impart to the agitator a maximum 15 amount of rubbing movement for each operation of the motor piston.

To this end it is a further object of the invention to provide means for positively imparting to the shaft carrying the agitator 20 both a reciprocatory and a rotatory movement; to directly connect this shaft to the motor; to provide means for adjusting the agitator to accommodate the same to the amount of material under treatment; and to 25 provide such a mechanism of a simple construction, thereby enabling a strong, durable mechanism to be built without materially increasing the size or weight of the machine.

With these objects in view my invention 30 consists in certain novel features of construction and in certain combinations and arrangements of parts hereinafter to be described, and then more particularly pointed out in the claims.

35 In the accompanying drawings, Figure 1 is a side elevation, partly in section, of a mechanism embodying my invention: Fig. 2 is a top plan view of the same; and Fig. 3 is a vertical, sectional view, taken centrally 40 through a portion of the mechanism.

In these drawings I have illustrated the 45 preferred form of my invention and have shown the same as applied to a washing machine of ordinary construction. The washing machine itself does not form a part of the invention and I have shown only so much of the lid 1 of the machine and the agitator 2 as are necessary to an understanding of the invention. The agitator 2, as here 50 shown, is of ordinary construction having a series of corrugations adapted to engage the material under treatment and is rigidly secured to the lower end of an agitator shaft 4 which extends upwardly through the lid 1.

Suitable means are connected to the shaft 4 55 for imparting both a reciprocatory and a rotatory movement thereto. This I prefer to accomplish by mounting the motor directly upon the shaft. In the present instance, the motor is shown as an oscillating 60 motor 5, of ordinary construction, and is provided with a centrally arranged hollow shaft 6 extending beyond the cylinder heads on each side of the motor and provided at each end with clutch members 7. This motor is so supported as to be held against rotary movement, but to be capable of a certain amount of reciprocating movement in a vertical plane. To this end I prefer to provide a supporting frame 8, which is here 65 shown as comprising top and bottom plates 9 and 10 having apertures arranged centrally thereof, as shown at 11 and 12. These plates are connected one to the other by bolts 13 extending through apertured arms 14 extending outwardly from the plates 9 and 10. Each plate is preferably provided with three of these arms, formed integral therewith, 70 each of which is adapted to receive one of the bolts 13. These bolts extend through 75 the lid 1 of the washing machine and serve to secure the frame to this lid. In order that the top and bottom plates 9 and 10 of the frame may be supported in their proper 80 positions relatively one to the other I insert 85 between these plates suitable spreaders, which, in the present instance, consist of tubes 15 surrounding the portions of the bolts 13 lying between the plates 9 and 10. These tubes are of a greater diameter than 90 the apertures in the arms 14, and, consequently, serve to retain the plates in their proper positions, and, when the nuts are 95 tightened down on the bolts 13, to form a rigid supporting frame. The motor may be 100 mounted on this frame in any suitable manner. In the present instance I have shown the lower cylinder head of the motor as provided with apertured lugs 16 adapted to receive the bolts and their surrounding tubes 105 15 which form a guide for the motor and serve to hold the same against rotary movement, but permit the same to reciprocate.

Reciprocally mounted in the apertures 11 and 12 of the plates 9 and 10, respectively, 110 are sleeves 17 which are provided at their inner ends with clutch members 18 adapted to coöperate with the clutch members 7 of

the motor shaft, thus causing the sleeve to rotate in unison with said shaft. Each sleeve is provided with one or more outwardly extending projections, which, in the present instance, consist of stud shafts 19 having mounted thereon antifriction rollers 20. These projections are adapted to engage suitable inclined guides carried by the upper and lower plates, respectively, and thus cause the sleeves 17 to reciprocate vertically as the motor shaft is oscillated. These inclined guides preferably consist of cams 21 mounted on the top and bottom plates. In the present instance I have shown these cams 15 as substantially V-shaped and formed integral with their respective plates 9 and 10. Each plate is preferably provided with two of these cams arranged on opposite sides of its central opening, the cams of one of the plates having their apices arranged in a vertical plane extending at substantially right angles to the planes of the apices of the cams of the other plate. Thus, it will be seen that the sleeves 17 form extensions of 20 the motor shaft and move in unison therewith, and that, by reason of the projections moving along the inclined guides, a reciprocating movement is imparted to the motor.

The shaft 4 of the agitator extends upwardly through the motor shaft and its extensions and has its upper end extending some distance beyond the upper sleeve or extension 17. The upper end of the shaft is cut away on one side so that it is substantially semicircular in cross section, as shown at 22, and is provided on its flat side with a series of teeth 23. An extension or collar 24 is rigidly secured to the upper end of the upper sleeve or motor shaft extension 17 and is provided with a central opening, corresponding in cross section to the cross sectional area of the portion 22 of the shaft 4, and having at one side of said opening a groove 25 to receive the teeth 23, thus enabling the shaft to be moved longitudinally in the collar 24 but holding the same against rotary movement relatively thereto. Suitable means are provided for locking the shaft 4 against longitudinal movement and 45 causing the same to move in unison with the motor shaft and its extensions. This means preferably comprises a latch 26 pivotally connected to one side of the collar 24, as shown at 27, and adapted to extend through 50 a slot 28 in the collar 24 and engage the teeth 23 of the shaft 4. A suitable spring is applied to the latch 26 to hold the same normally in engagement with the teeth of the shaft 4 and, in the present instance, this 55 spring consists of a flat spring 29 secured at one end to the collar and having its other end adapted to engage a toe or projection 30 formed on the latch 26 at a point beyond its pivotal connection to the collar 24 and tending 60 to move the latch 26 about its pivotal 65

center and toward the shaft 4. The latch has a handle 31, by means of which it may be moved outwardly against the tension of the spring 29 to release the shaft 4 and enable the same to be moved longitudinally by 70 means of a handle 32 secured to the upper end thereof.

The operation of the device will be readily understood from the foregoing description and it will be apparent that, as the motor shaft operates within the casing 5, the agitator shaft 4 will be carried therewith and a rotary movement imparted to the agitator 2. As the motor shaft rotates the projections carried by the extensions at the opposite ends thereof will engage the inclined guides carried by the supporting frame and will cause the motor shaft and the motor to reciprocate vertically. By arranging the cams on the top and bottom plates of the 80 supporting frame alternately a positive downward movement is imparted to the shaft on both strokes of the oscillating piston, the cam of the upper plate serving, in the present instance, to force the shaft down and the cam of the lower plate serving to elevate the shaft. In this manner I secure a maximum amount of rubbing action for each oscillation of the motor shaft and both the rotary movement and the reciprocatory 90 movement are positive, thus adding greatly to the efficiency of the machine. Further, the shaft of the agitator is so connected to the motor shaft as to move in unison therewith and to enable the agitator shaft to be 100 adjusted relatively to the motor shaft, thus adjusting the agitator to accommodate the same to the amount of material under treatment. Further, by mounting the motor directly upon the agitator shaft I eliminate all 105 intermediate gearing and apply the power directly to the agitator, thus greatly increasing the efficiency of the mechanism. It will also be apparent that I have provided an operating mechanism of a very simple character, comprising a minimum number of parts and having these parts of such a construction as to enable the same to be made of strong, durable material without adding materially to the size or weight of the mechanism, thus insuring against breakage and adding to the life of the mechanism without rendering the same unwieldy.

I wish it to be understood that I do not desire to be limited to the details of construction shown and described, for obvious modifications will occur to a person skilled in the art.

It will be understood that while I have shown and described the invention in connection with the agitator shaft of a washing machine, it is not limited to this use, but may be utilized in connection with other devices in which it is desirable to impart a similar movement to a shaft.

Having thus fully described my invention, what I claim as new and desire to secure by Letters Patent, is:—

1. A mechanism of the character described comprising a supporting frame, a member reciprocally mounted on said frame and held against rotation relatively thereto, a shaft rotatably mounted in said member and held against reciprocation relatively thereto, means for rotating said shaft, inclined guides arranged on opposite sides of said shaft, projections carried by said shaft and adapted to engage said inclined guides, a part to be actuated, and means for connecting said part to said shaft. 5
2. A mechanism of the character described comprising a frame, a motor mounted on said frame and capable of a reciprocating movement thereon, a shaft connected to said motor, means actuated by the operation of said motor for imparting a reciprocatory movement to said motor and to said shaft, a part to be actuated, and means for connecting said part to said shaft. 10
3. In a mechanism of the character described, the combination, with a supporting frame, a motor mounted to reciprocate thereon and held against rotary movement relatively thereto, a shaft actuated by said motor, and means for imparting a reciprocatory movement to said motor and to said shaft, of a part to be actuated, and means for connecting said part to be actuated to said shaft. 15
4. In a mechanism of the character described, the combination, with a supporting frame, a motor reciprocally mounted on said frame and held against rotation relatively thereto, a shaft for said motor, a laterally extending projection carried by said shaft, and an inclined guide adapted to be engaged by said projection, of a part to be actuated, and means for connecting said part to be actuated to said shaft. 20
5. In a mechanism of the character described, the combination, with a supporting frame, a shaft rotatably and reciprocally mounted in said frame, oppositely arranged inclined guides supported one above the other on said frame, laterally extending projections carried by said shaft and adapted to engage said guides, and means for imparting a rocking movement to said shaft, of a part to be actuated, and means for connecting said shaft to said part to be actuated. 25
6. In a mechanism of the character described, the combination, with a supporting frame, a motor mounted to reciprocate thereon and held against rotatory movement relatively thereto, a shaft for said motor, and means for imparting a reciprocatory movement to said motor and said shaft, of a second shaft, and means for connecting said second shaft to said motor shaft. 30
7. In a mechanism of the character de- 35
- scribed, the combination, with a supporting frame, a motor mounted to reciprocate thereon and held against rotatory movement relatively thereto, a shaft for said motor, and means for imparting a reciprocatory movement to said motor and said shaft, of a second shaft, and means for adjustingably connecting said second shaft to said motor shaft. 70
8. In a mechanism of the character described, the combination, with a supporting frame, a motor reciprocally mounted thereon and held against rotation relatively thereto, a hollow shaft for said motor, and means for imparting a reciprocatory movement to said shaft and said motor, of a second shaft 75 extending through said hollow motor shaft, and means for rigidly connecting said second shaft to said motor shaft. 80
9. In a mechanism of the character described, the combination, with a supporting frame, a motor reciprocally mounted on said frame and held against rotation relatively thereto, a shaft for said motor, a laterally extending projection carried by said shaft, and an inclined guide adapted to be engaged by said projection, of a second shaft, and means for securing said second shaft to said motor shaft. 85
10. In a mechanism of the character described, the combination, with a supporting frame, a motor reciprocally mounted thereon and held against rotatory movement relatively thereto, a shaft for said motor, laterally extending projections carried by said shaft above and below said motor, and inclined guideways arranged above and below said motor adapted to be engaged by the respective projections, of a second shaft, and means for connecting said second shaft to said motor shaft. 90
11. A mechanism of the character described comprising a supporting frame, a motor reciprocally mounted thereon and held against rotation relatively thereto, a hollow shaft for said motor, an extension to said shaft, a lateral projection carried by said extension, and a guideway adapted to be engaged by said projection, of a second shaft, and means for securing said second shaft to said motor shaft. 95
12. In a mechanism of the character described, the combination, with a supporting frame, a motor reciprocally mounted thereon and held against rotation relatively thereto, a shaft for said motor extending through both cylinder heads thereof, extensions for each end of said shaft, projections carried by said extensions, oppositely arranged inclined guides located above and below said motor and adapted to be engaged by said projection, of a second shaft, and means for connecting said second shaft to said motor shaft. 100
13. In a mechanism of the character described, a supporting frame comprising top and bottom plates, each having a central 105
14. In a mechanism of the character described, a supporting frame comprising top and bottom plates, each having a central 110
15. In a mechanism of the character described, a supporting frame comprising top and bottom plates, each having a central 115
16. In a mechanism of the character described, a supporting frame comprising top and bottom plates, each having a central 120
17. In a mechanism of the character described, a supporting frame comprising top and bottom plates, each having a central 125
18. In a mechanism of the character described, a supporting frame comprising top and bottom plates, each having a central 130

aperture, guide rods connecting said plates, a motor slidably mounted on said guide rods, a hollow shaft for said motor, extensions for said shaft arranged above and below said 5 motor and extending through the apertures in said plates, projections carried by said extensions, inclined guides carried by said plates and adapted to be engaged by said projections, and a shaft extending through 10 said motor shaft and the extensions therefor and adapted to move in unison therewith.

14. In a mechanism of the character described, a supporting frame comprising top 15 and bottom plates, each having a central aperture, inwardly extending cams secured to each of said plates on the opposite sides of the aperture therein, rods connecting said top and bottom plates, a motor slidably 20 mounted on said frame between said top and bottom plates, a shaft for said motor, extensions for said shaft extending above and below said motor and through the apertures in said top and bottom plates, respectively, 25 projections carried by said extensions and adapted to engage said cams, and a shaft connected to said motor shaft and adapted to move in unison therewith.

15. In a mechanism of the character described, a supporting frame comprising top 30 and bottom plates, each having a central aperture, inwardly extending cams secured to each of said plates on the opposite sides of the aperture therein, the apices of the 35 cams on one of said plates being arranged in a plane extending at substantially right angles to the apices of the cams carried by the other of said plates, rods connecting said top and bottom plates, a motor slidably 40 mounted on said rods between said top and bottom plates, a shaft for said motor, extensions for said shaft extending above and below said motor and through the apertures in said top and bottom plate, respectively, 45 projections carried by said extensions and adapted to engage said cams, and a shaft connected to said motor shaft and adapted to move in unison therewith.

16. In a mechanism of the character described, a supporting frame comprising top 50 and bottom plates, each having a central aperture, inwardly extending cams secured to each of said plates on the opposite sides of the aperture therein, rods connecting said 55 top and bottom plates, tubular members surrounding said rods and engaging said top and bottom plates, a motor slidably mounted on said rods between said top and bottom plates, a shaft for said motor, extensions for 60 said shaft extending above and below said motor and through the apertures in said top and bottom plates, respectively, projections carried by said extensions and adapted to engage said cams, and a shaft connected to

said motor shaft and adapted to move in 65 unison therewith.

17. In a mechanism of the character described, the combination, with a supporting frame, a motor reciprocally mounted thereon and held against rotation relatively thereto, a hollow shaft for said motor, hollow extensions arranged above and below said motor, projections carried by said extensions, and inclined guides carried by said supporting frame above and below said motor and 70 adapted to be engaged by said projections, of a shaft extending through said hollow motor shaft and its extensions, and means carried by the upper extension for locking the last-mentioned shaft against movement 75 relatively to said extension and said motor shaft.

18. In a mechanism of the character described, the combination, with a supporting frame, a motor reciprocally mounted thereon 85 and held against rotation relatively thereto, a hollow shaft for said motor, hollow extensions arranged above and below said motor, projections carried by said extensions, and inclined guides carried by said supporting 90 frame above and below said motor and adapted to be engaged by said projections, of a shaft extending through said motor shaft and the extensions therefor and having a portion of its length non-circular in 95 cross section, a part carried by one of said extensions having an opening corresponding to the cross sectional area of said shaft, and a member carried by said part and adapted to engage said shaft to hold the same 100 against longitudinal movement relatively to said extension and said motor shaft.

19. In a mechanism of the character described, the combination, with a supporting frame, a motor reciprocally mounted thereon 105 and held against rotation relatively thereto, a hollow shaft for said motor, hollow extensions arranged above and below said motor, projections carried by said extensions, and inclined guides carried by said supporting 110 frame above and below said motor and adapted to be engaged by said projections, of a shaft extending through said hollow motor shaft and its extensions, having one side flattened for a portion of its length and 115 provided with teeth, a collar carried by one of said extensions and adapted to receive the flat side portion of said shaft to hold the same against rotatory movement relatively thereto, and a latch carried by said collar 120 and adapted to engage the teeth in said shaft to lock the same against longitudinal movement relatively to said extensions and said motor shaft.

20. In a mechanism of the character de- 125 scribed, the combination, with a supporting frame comprising top and bottom plates, each having a central aperture, cams carried

by each of said plates and arranged on opposite sides of the central opening therein, the cams of each of said plates extending toward the other of said plates and having their apices arranged in a plane extending at substantially right angles to the plane of the apices of the cams of the other plate, rods connecting said top and bottom plates, tubular members surrounding said rods and 1) having their opposite ends in engagement with said plates, a motor slidably mounted on said tubular members, a hollow shaft for said motor, extensions for said shaft arranged above and below said motor, extend-

ing through the aperture in the adjacent 15 plate, projections carried by said extensions and adapted to engage the adjacent cam, of a second shaft extending through said hollow motor shaft and its extensions, and means for locking said second shaft against 20 either longitudinal or rotatory movement relatively to said motor shaft.

In testimony whereof, I affix my signature in presence of two witnesses.
